UNITED STATES PATENT OFFICE

JOSEPH H. McFAUL, OF QUEENS VILLAGE, NEW YORK, ASSIGNOR TO CARY PRODUCTS COMPANY, INC., OF CHICAGO, ILLINOIS, A CORPORATION OF DELAWARE

DESIGN FOR A METALLIC MATTING

Application filed April 11, 1932. Serial No. 43,462. Term of patent 14 years.

To all whom it may concern:

Be it known that I, JOSEPH H. McFAUL, a citizen of the United States, residing at Queens Village, Long Island, in the county of Queens and State of New York, have invented a new, original, and ornamental Design for a Metallic Matting, of which the following is a specification, reference being had to the accompanying drawing, forming a part hereof.

In the accompanying drawing:

Fig. 1 is a plan view of a section of metallic matting showing my new design; and
Fig. 2 is a sectional view of the matting, taken on the line 2—2 of Fig. 1.

I claim:

The ornamental design for a metallic matting, substantially as shown.

JOSEPH H. McFAUL.
